ELASTIC LINK STRAPS

Ludwig Kunzmann, Pforzheim, Germany, assignor to Rodi & Wienenberger Aktiengesellschaft, Pforzheim, Germany

Application October 30, 1956, Serial No. 619,198

Claims priority, application Germany October 4, 1956

3 Claims. (Cl. 59—79)

The present invention relates to new improvements in elastic link straps for ornamental or utilitarian purposes, and especially in watch bracelets. More particularly, the invention relates to that type of elastic link straps which consists of two superimposed layers of links which in the contracted position of the strap are staggered relative to each other by the width of one-half link as seen in the longitudinal direction of the strap, and in which the individual upper and lower links form hollow casings, the respective lower and upper sides of which facing toward each other are open, while the transverse side walls of the adjacent links of one layer engage into the links of the other layer, and wherein curved leaf springs are mounted between these side walls which are pressed flat when the strap is being expanded.

It is an object of the present invention to provide certain new and useful improvements in an elastic link strap of the general type as described above in which the upper and lower links are connected with each other so as to be movable relative to each other in the longitudinal direction of the strap.

A feature of the invention for attaining this object consists in providing the transverse side walls of the links of one layer with slots which extend inwardly from a point at or near the outer edges of the links, and in providing each of the links of the other layer with extensions at the opposite ends thereof which are then bent so as to form a pair of transversely extending tabs or crossbars which project into the slots in the links of the other layer and thus serve both as connecting members for securing the upper and lower links to each other, and as guiding members along which the slotted links of the other layer may slide in the longitudinal direction of the strap relative to the links carrying these transverse tabs or crossbars.

In several preferred embodiments of the invention, this feature consists in providing the outer ends of the lower links with slots extending toward each other, and in bending a pair of outer extensions of the upper ornamental wall of the upper links downwardly and then toward each other and into the slots in the ends of the lower links so as to be slidably therein in the longitudinal direction of the strap.

It is another important object of the invention to provide an elastic two-layer link strap of the smallest possible thickness.

According to one embodiment of the invention this object is attained by making the lower links in the form of a substantially flat bottom plate with a pair of side walls thereon extending at substantially right angles thereto and transversely to the longitudinal direction of the strap. These side walls of the lower links are provided at their outer ends with projecting tongues which preferably are rounded off semicircularly at their outer ends, while the extensions of the upper wall of the upper links are bent downwardly over these semicircular tongues and inwardly toward each other and into the outer slots

2

in the lower links so as then to form semicylindrical portions. The height of the side walls of the lower links which are designed to extend into the upper links through the lower opening thereof, and the height or width of the tongues on these side walls may be made of any desired size and in accordance with the dimensions of the upper links so as to make the combined thickness of the upper and lower links as small as possible. For this purpose, the slots in the ends of the side walls of the lower links are preferably disposed so as to be immediately above the bottom plate thereof so that the latter forms the lower edges defining the slots.

According to another embodiment of the invention, the thickness of the strap may be further reduced so that the lower links will not add at all to the thickness of the upper links and the entire thickness of the two-layer strap will be merely that of the upper links. For this purpose, the slots in the side walls of the lower links are provided at such a low point so that they will remain only in the form of notches or recesses in the lower outer ends of the side walls, each being limited only by its inner edge and the lower edge of the projecting tongue over which the respective extension of the upper ornamental wall of the upper link is bent. The bottom plate of each lower link is then shortened at both ends to the inner end of the notch or recess, and such notches are then only made of a width in the vertical direction so as to correspond substantially to the thickness of the material of the extensions of the upper link walls which are bent toward each other into such notches.

Another object of the present invention is to simplify the design and construction of the various elements of a two-layer link strap, and to reduce the cost of production of such a strap. According to one embodiment

of the invention this object as well as the object previously mentioned of producing a two-layer strap of the smallest possible thickness is attained by making the upper and lower links of identical design and preferably also of identical shape and dimensions so that the entire strap will then only consist of two different types of elements, namely, the links and the leaf springs, and the adjacent upper and lower links will be contained within each other and the thickness of the strap will be no more than the thickness of the upper links plus the thickness of the material of the bottom plate of the lower links. Both the upper and lower links are then similar to the lower links of one of the first-described embodiments of the invention and each consist of a substantially flat outer plate with side walls thereon extending at right angles thereto and provided with slots at the outer ends thereof which are formed by the space between the tongues projecting outwardly from the lower ends of the side walls of the upper links and the upper ends of the side walls of the lower links, respectively and the extensions of the respective outer walls of the upper and lower links, that is, the ornamental upper wall of the upper links and the bottom plate of the lower links, which are bent toward the links of the other layer and then inwardly toward each other. These bent-over extensions then form pockets at both ends of each link in which the tongues of the links of the other layer are guided for movement in the longitudinal direction of the strap when the upper and lower links are inserted into each other.

According to still another embodiment of the invention, the slots are provided in the side walls of the links of one layer and, in the assembled structure, the respective outer walls of such links, that is, the ornamental walls of the upper links or the bottom walls of the lower links, respectively, are outwardly extended, and these extensions are bent over to close the slots in the out-

ward direction. Since the outer ends of the slots are thus closed, it is no longer possible to insert the extensions of the outer wall of the links of the other layer into them from the outside to connect the upper and lower links to each other, but it is then necessary to provide a crossbar at each end of the links opposite to those in which the mentioned slots are provided, and to insert such crossbars into the slots. These crossbars are likewise formed by extensions of the walls of the latter links, but in this case they are not provided on the outer wall as in the previously described embodiments but on the side walls of these links and at a level depending upon the level of the slots or apertures in the side walls of the opposite links. These extensions are made of a thickness substantially corresponding to the width of the slots in the other links, as seen in the vertical direction, while the length of the slots is then also made so as to correspond substantially to the thickness of the material of the links and the extensions thereon. The extensions at the corresponding ends of both side walls of these links are then bent toward each other so as to form a crossbar which is inserted into the slots in the side walls of two adjacent links carrying the crossbars and are guided thereon for movement in the longitudinal direction of the strap. In order to close the lateral edges of the strap completely when in the contracted position, the outer wall of the links carrying the crossbars may also be extended at both ends and such extensions be bent over toward the other layer so as to cover the crossbars and close the partly open ends of these links. The free ends of the bent-over extensions of the links of both layers then face each other and slide closely along each other when the strap is being expanded or contracted. The thickness of the strap according to this embodiment of the invention is therefore likewise equal to the thickness of the link of only one layer plus the thickness of the material of one outer link wall. A further object of the present invention is to provide a two-layer elastic link strap of the type as previously described, the individual links of which may be easily separated from each other without unbending any parts thereof to permit the strap to be lengthened or shortened by the insertion of additional links or the removal of one or more links.

Another object of the invention is to provide such a strap with means which will only permit the individual links to be separated intentionally and will prevent the strap from ever coming apart accidentally.

This object may be attained in the embodiments of the invention as first described by providing at least some of the upper links with a recess or cutout at or near one outer corner of the free edge of one of the two bent-over extensions adjacent to one side wall of such links, and by shortening the respective tongue on the side wall of one of the two lower links which is being overlapped by such extension to such an extent that such shortened tongue may be slipped through such cutout and the respective lower link may be unhooked from the upper link. In order to prevent the links from becoming unintentionally unhooked from each other, it is merely necessary to shorten one tongue of that of two adjacent lower links entering into one upper link which moves away from the cutout at one side of the free edge of the bent-over extension of the upper link when the strap is being expanded.

Another feature of the invention for shortening or lengthening the elastic strap according to the first described embodiments consists in shortening the tongues at both ends of one side wall of at least some of the lower links to such an extent that such side wall may be inserted between or slipped out from the bent-over extensions of the adjacent upper link. A suitable connecting member is then provided within such upper link, and the outer ends of such connecting member are provided with recesses at its lower side so as substantially to cor-

respond in shape to the notches or slots in the uncut side wall of the lower link. The bent-over extensions of the upper link engage into these lower recesses in the connecting member and thus retain the same in the upper link, but so as to be slideable in the longitudinal direction of the strap. The bottom wall of the respective lower link is then provided with a hole in which a screw is mounted which is screwed into a threaded hole in the connecting member to secure the latter removably to such lower link. Particularly if the individual links of the strap are to be made very narrow, each of the connecting members may be provided with a central reinforcing portion for receiving the screw hole, while one side wall of the upper link may then be provided with a corresponding cutout for receiving such reinforcing portion. However, the connecting member may also be made of angular shape, one arm of which is provided to abut against one side wall of the upper link, while the other arm abuts against the bottom wall of the lower link to which it may be removably secured.

In all of the embodiments of the invention as previously described, it is advisable to make the lower links of smaller width than the upper links so that gaps will remain between the adjacent lower links even when the strap is in its completely contracted position and the skin and hairs on the hand and wrist of the wearer cannot be caught between these links.

Further objects, features, and advantages of the present invention will appear from the following detailed description thereof, particularly when read with reference to the accompanying drawings, in which:

Fig. 1 shows, partly in cross section, a side view of a portion of a link strap illustrating the principle of the present invention;

Fig. 2 shows a cross section taken along line II—II of Fig. 1;

Fig. 3 shows a perspective view of an upper link according to a first embodiment of the invention;

Fig. 4 shows a perspective view of the corresponding lower link;

Fig. 5 shows a perspective view of a leaf spring;

Fig. 6 shows a fractional cross section of an upper and lower link according to Figs. 3 and 4 in their engaged position with each other, as seen in a direction transverse to the longitudinal direction of the strap;

Fig. 7 shows a view similar to Fig. 6 of a modification of the lower link;

Fig. 8 shows a perspective view of an upper link according to Fig. 3, but in the inverted position;

Fig. 9 shows a horizontal cross section through two links in the process of being disengaged from each other when the strap is to be shortened;

Fig. 10 shows a vertical longitudinal cross section through two links of both layers according to another embodiment of the invention;

Fig. 11 shows a perspective view of a lower link according to Fig. 10;

Fig. 12 shows a perspective view of a connecting member according to Fig. 10;

Fig. 13 shows a perspective view of a modified connecting member;

Fig. 14 shows a perspective view of an upper link to be used in combination with a connecting member according to Fig. 13;

Fig. 15 shows a perspective view of an upper link according to another modification of the invention;

Fig. 16 shows a perspective view of the corresponding lower link;

Fig. 17 shows a perspective view of an upper link of still another modification of the invention; while

Fig. 18 shows a perspective view of the corresponding lower link.

Referring to the drawings, and first particularly to Figs. 1 and 2 which are merely intended to illustrate the basic principles of the present invention, the new elastic link

strap consists generally of a plurality of upper links 10 which form hollow casings which are open in the downward direction, and each of which has an upper wall 11, side walls 12, end walls 13 which form downwardly bent extensions of the upper wall 11, and inwardly bent tabs or bars 15 which form extensions either of the end walls 13, as shown in Figs. 1 and 2, or of side walls 12. The lower links 30 are open in the upward direction and each have a bottom wall, transverse side walls 31, and end walls 33, which end walls may, however, be omitted according to some embodiments of the invention, their function then being taken over by the end walls of the upper links. One side wall 31 of each of two adjacent lower links 30 projects into one upper link 10, and these side walls 31 are provided at or near the outer ends with slots or recesses 32. Extensions 15 of the upper links 10 are bent inwardly so as to engage into these slots 32 to connect the upper and lower links 10 and 30 with each other so as to be slideable relative to each other in the longitudinal direction of the strap. The upper links 10 further contain leaf springs 50, and these springs are inserted between at least one of the side walls 12 of each upper link and one side wall 31 of at least one of the two associated lower links 30, and are pressed flat between these side walls when the strap is being expanded, thus tending to contract the strap.

The strap as illustrated in Figs. 1 and 2, although thinner than previous two-layer straps, is still relatively thick. Also, due to the troublous shape of the lower links 30, dirt may easily collect therein. This will be avoided in the embodiments of the invention, as shown in Figs. 3 to 14. The lower links 34 of the embodiment shown in Fig. 4 are therefore devoid of any end walls and only consist of a substantially flat bottom plate 35 with two side walls 36 extending upwardly therefrom at a right angle thereto and provided at each end with a tongue 37 extending beyond bottom plate 35 and preferably rounded off semi-circularly. Between tongues 37 and the upper edges of bottom plate 35 and directly adjacent thereto, side walls 36 are provided with inwardly extending slots or recesses 38. The corresponding upper link 15, as shown in Fig. 3, consists of an upper plate 16 which forms a part of the ornamental surface of the strap, side walls 17 extending transversely to the longitudinal direction of the strap, and outer extensions on upper plate 16 which are bent over downwardly and then inwardly so as to form semicircular end walls terminating in opposite tabs 18. The ends of side walls 17 are provided with notches 19. When the individual parts of the strap are being assembled and extensions 18 are then bent downwardly and inwardly and into notches 19, as shown in Figs. 3 and 6, they will curve around tongues 37 of lower links 30 and the lower surfaces of their inwardly bent ends will then be disposed at an even level with the edges of side walls 17 defining the bottom opening of each upper link and extend into slots 38 in side walls 36 of the lower links so as to be slideable therein in the longitudinal direction of the strap. During such assembly, a pair of curved leaf springs 50 is also inserted into each upper link 15 so that each spring will then be mounted between one side wall 17 of an upper link 15 and the corresponding side wall 36 of one of the two lower links 34 which are associated with such upper link, as shown in Figs. 1 and 9. Each spring 50 is undercut at its lower side near its outer rounded ends so as to form bearing surfaces 51 on which springs 50 may rest on the rounded inner end surfaces of extensions 18 of upper links 15.

Fig. 7 shows a modification of the lower links 34. Bottom plate 35' is shortened at each end, as compared with the embodiment shown in Figs. 4 and 6, and side walls 37' are notched out accordingly by substantially the thickness of the material of tabs 18 of upper links 15. This embodiment therefore does not require any special slots in side walls 37' thereof, and the assembled upper and lower links will be still thinner than those shown in

Fig. 6 since the lower surface of the inwardly bent tabs 18 of the upper links will be at the same level as the lower surface of bottom plate 35' of the lower links.

While the elastic strap as previously described does not permit any removal of any links or insertion of additional links in order to adjust the strap to a smaller or thicker wrist, unless one or more upper links are unbent and then rebent to disconnect them from the lower links, as well as from each other, and to reconnect them there-to, Figs. 4, 8 and 9 also illustrate a modification of the invention which permits such removal or insertion of one or more links to be carried out without any tools and without bending or unbending any links which might leave permanent marks on the strap and harm the appearance thereof.

Fig. 8 illustrates one of the upper links as shown in Fig. 3 in the inverted position. While in the previously described embodiment it was assumed that tabs 18 forming the bent-over ends of the extensions of upper plate 16 of the upper links extended fully from one side wall 17 thereof to the other, Fig. 8 shows one end of one of the two tabs 18 as being provided with a recess or cutout 20. If this cutout 20 should be hidden from the outside, it may be made of U-shape so that a narrow outer tongue 25 will close the respective notch 19 in the adjacent side wall 17, or such notch may be made of shorter length. If the corresponding tongue 37" on one side wall 36 of one of the two lower links 34 which are associated with the respective upper link is shortened, as indicated in Fig. 30 by cross-hatching, it will then be easily possible to unhook such lower link 34 from the upper link 15. It is for this purpose only necessary first to expand the strap so that leaf springs 50 will be flattened completely between side walls 36 of lower links 34 and side walls 35 35 of the upper links, and then, while holding the adjacent links in such expanded position, to turn one of the lower links 34 which has such a shortened tongue 37" to an oblique position opposite to the direction of expansion of the strap, as illustrated in Fig. 9, so that the end 40 of the side wall of such lower link which carries the shortened tongue 37" will be pushed back and placed in line with the cutout 20. The shortened tongue 37" may then be slipped through cutout 20, and the other full tongue 37 on such side wall 36 may then also be 45 unhooked from the opposite tab 18 of the upper link 15. In the same manner it is also possible again to hook the lower link 34 into the respective upper link 15. In order to prevent the links from becoming unhooked unintentionally, it is advisable to provide the shortened tongue 50 37" on the side wall 36 of that of the two lower links engaging into the respective upper link 15 which is moved away from, rather than toward, cutout 20 in the upper link. This cutout 20 should, however, only be made of a depth so as still to leave a sufficiently large supporting 55 surface between its edge and the outer end of the full or uncut tongue 37 of the side wall of the adjacent lower link so that this tongue can under no circumstances slip out through this cutout 20. Figs. 10 to 14 illustrate another possibility according to the invention of shortening the new strap. The lower link 40 in Fig. 11 corresponds in shape generally to lower link 34 as shown in Fig. 4 insofar as it also has a bottom plate 41 and two side walls 42 and 43 at right angles thereto, and that one side wall 42 also has a tongue 44 at each end. 60 However, the other side wall 43 does not have any outer tongues. This shortened side wall 43 may therefore be inserted between the ends of the inwardly projecting tabs 18 of the upper link 15, which is of a general shape similar to that shown in Figs. 3 to 9, without requiring these tabs 18 to be unbent. Aside from one spring 50, each upper link 15 contains an angular connecting member 45, as shown in Figs. 10 and 12, the higher side of which engages with the inner surface of one side wall 17 when the strap is in the released position, and the outer ends of which are provided at the lower side thereof

with recesses 46 into which tabs 18 of the upper link 15 project so as to secure connecting member 45 thereto. Connecting member 45 is then removably secured to the bottom plate 41 of the lower link 40 by a screw 47. Thus, after screw 47 has been removed, the shorter side wall 43 may then be removed from the upper link 15 without requiring tabs 18 to be unbent.

If the links of the strap are made very narrow, it may be advisable or necessary to reinforce or enlarge the central part of connecting member 48 so as to provide sufficient material for the wall of the bore for screw 47. In such a case, connecting member 48 may be made of a shape as shown in Fig. 13, in which the central part thereof has a reinforcing projection 49, while the upper link 15, as shown in Fig. 14, is provided with a central cutout 21 in its one side wall 17' which is adapted to receive the projection 49.

Since it is hardly ever necessary that more than a few links be removed to shorten the strap sufficiently to comply with the circumference of the wrist of any wearer thereof, only a few links need be made removable in either of the ways as described above. For easier identification, such removable links may then preferably be marked in a suitable manner, for example, on the lower surface of the lower links.

Figs. 15 and 16 illustrate a modification of the upper and lower links according to the invention and of the means of connecting and guiding the same relative to each other. The upper and lower links 60 and 70, respectively, are of exactly the same shape and consist of a substantially flat plate 61 or 71 which forms either the outer ornamental surface of the upper link 60 or the lower arm-engaging surface of the lower link 70, respectively, and carries a pair of side walls 62 or 72, respectively, in which horizontal slots 63 or 73 are provided at the outer ends thereof which thus form outer tongues 64 or 74, respectively. The outer end portions of the flat plates 61 and 71 are bent over downwardly or upwardly, respectively, and their free ends project into slots 63 and 73, respectively, of the same links so as to form pockets 66 and 76, respectively, in which tongues 74 and 64 of the respective link of the other layer may slide in the longitudinal direction of the strap. The upper and lower links are therefore doubly engaged with each other at both sides of the strap and thus cover each other. Leaf springs are again provided between side walls 62 and 72 of the adjacent links and are pressed flat by them when the strap is being expanded. When the strap according to Figs. 15 and 16 is being assembled, the upper and lower links 60 and 70 are first inserted into each other and the springs inserted between side walls 62 and 72 while the ends 65 and 75 are still unbent. Thereafter, ends 65 of upper links 60 and ends 75 of the lower links 70 are bent over and around tongues 74 of the lower links and tongues 64 of the upper links, and into slots 63 and 73 in side walls 62 and 72, respectively, so that tongues 74 of lower links 70 are enclosed by the ends 65 of the upper links 60 and tongues 64 of the upper links 60 by the ends 75 of the lower links 70. Also in this embodiment of the invention it is preferred to round off the tongues 64 and 76 semicircularly so that the overlapping ends 65 and 75 will be of a similar semicylindrical shape.

While in each of the embodiments of the invention as previously described the upper and lower links are connected to and guided along each other by the bent-over tabs or ends of the outer walls of the links of one or both layers, the arrangement is made slightly different in the embodiment shown in Figs. 17 and 18, insofar as herein the lower links 90 are provided with cross arms 94 which, when the strap is assembled, engage in slots 83 in the side walls 82 of upper links 80. Each of the upper links 80 again consists of an upper ornamental plate 81 with side walls 82 thereon and at right angles thereto, and bent-over ends 85 of plate 81 which together

form the lateral edges of the strap. The lower links 90 consist of a bottom plate 91 with side walls 92 at right angles thereto, and a pair of cross arms 94 on each side wall 92 which are also bent at right angles and toward those of the other side wall 92. The bent-over ends 85 of the upper links 80 of this embodiment only serve to cover the end openings of the lower links 90. These links may, however, also be provided with end walls 95 which form extensions of the bottom plate 91 and are bent upwardly either so as to be in sliding engagement with the lower edges of the ends 85 of the upper links or to overlap these ends or to be overlapped thereby. Of course, the arrangement may also be reversed so that the cross arms 94 may be provided on the upper links 80 and slots 83 in the lower links 92. Similarly, the strap according to the other embodiments of the invention may be reversed so that the upper links as shown in the drawings serve as lower links and the lower links as upper links.

In all of the embodiments of the invention, it is advisable to make the width of the lower links smaller than that of the upper links so that gaps will be formed between the adjacent lower links when the strap is in the fully contracted position when the adjacent upper links engage each other, whereby the skin or hairs on the hand and wrist of the wearer will not be caught between the edges of the lower links.

Although the invention has been illustrated and described with reference to the preferred embodiments thereof, it is to be understood that it is in no way limited to the details of such embodiments, but is capable of numerous modifications within the scope of the appended claims.

The invention having now been fully described, what is claimed is:

1. An elastic link strap comprising, in combination, a set of first links, each first link having a main wall including two inwardly opening channel-shaped end portions extending in longitudinal direction of the link strap and a pair of transverse first side walls so that each first link has a rectangular opening between said first side walls and the free edges of said channel-shaped end portions, at least one of said channel-shaped end portions having in the free edge thereof a cut-out adjacent one of said first side walls located at one corner of said rectangular opening; a set of second links alternately arranged with said first links, each second link having a main wall and two transverse second side walls and being arranged with said second side walls respectively located in two adjacent first links and passing through the respective openings, one of said second side walls having at each end thereof a longer extension and the other of said second side walls of each second link having only at one end thereof a longer extension and at the other end thereof a shorter extension, said extensions projecting into said channel-shaped end portions of the respective associated first link, one of said longer extensions of said one second side wall slidably engaging said cut-out edge also in the region of said cut-out, and said shorter extension of said other second side wall slidably engaging said cut-out edge only outside of said cut-out, said other second side walls being longer than the transverse distance between said free edges of said channel-shaped end portions, and the length of said other second side wall from the inner end of its longer extension to the outer free end of said shorter extension being shorter than the distance between the deepest point of said cut-out in said one corner and the diagonally opposite corner of said rectangular opening so that said shorter extension passes through said cut-out only when the respective other second side wall is placed in contracted position of said link strap in the diagonal of said rectangular opening whereby said second links can be threaded through said cut-outs for removal, said one second side wall of each second link being normally located in the longitudinal direction of the strap.

cated opposite said one of said first side walls of the associated first link; and a set of resilient means, each resilient means being located between a first side wall and a second side wall to urge said link chain into a contracted position.

2. An elastic link strap comprising, in combination, a set of first links, each first link having a main wall including two inwardly opening channel-shaped end portions extending in longitudinal direction of the link strap and a pair of transverse first side walls so that each first link has a rectangular opening between said first side walls and the free edges of said channel-shaped end portions, at least one of said channel-shaped end portions having in the free edge thereof a cut-out adjacent one of said first side walls located at one corner of said rectangular opening; a set of second links alternately arranged with said first links, each second link having a main wall and two transverse second side walls and being arranged with said second side walls respectively located in two adjacent first links and passing through the respective openings, the longitudinal edges of said main walls of said second links being located opposite the free edges of said channel-shaped end portions of the associated first links so as to form a flush surface, one of said second side walls having at each end thereof a longer extension and the other of said second side walls of each second link having only at one end thereof a longer extension and at the other end thereof a shorter extension, said extensions projecting into said channel-shaped end portions of the respective associated first link, one of said longer extensions of said one second side wall slidably engaging said cutout edge also in the region of said cut-out, and said shorter extension of said other second side wall slidably engaging said cutout edge only outside of said cut-out, said other second side walls being longer than the transverse distance between said free edges of said channel-shaped end portions, and the length of said other second side wall from the inner end of its longer extension to the outer free end of said shorter extension being shorter than the distance between the deepest point of said cut-out in said one corner and the diagonally opposite corner of said rectangular opening so that said shorter extension passes through said cut-out only when the respective other second side wall is placed in contracted position of said link strap in the diagonal of said rectangular opening whereby said second links can be threaded through said cut-outs for removal, said one second side wall of each second link being located opposite said one of said first side walls of the associated first link; and a set of resilient means, each resilient means being located between a first side wall and a second side wall to urge said link chain into a contracted position.

3. An elastic link strap comprising, in combination, a set of first links, each first link having a main wall including two inwardly opening channel-shaped end portions extending in longitudinal direction of the link strap and a pair of transverse first side walls so that each first link has a rectangular opening between said first side

walls and the free edges of said channel-shaped end portions, at least one of said channel-shaped end portions having in the free edge thereof a cut-out adjacent one of said first side walls located at one corner of said rectangular opening; a set of second links alternately arranged with said first links, each second link having a main wall and two transverse second side walls and being arranged with said second side walls respectively located in two adjacent first links and passing through the respective openings, one of said second side walls having at each end thereof a longer extension and the other of said second side walls of each second link having only at one end thereof a longer extension and at the other end thereof a shorter extension, said extensions projecting into said channel-shaped end portions of the respective associated first link, one of said longer extensions of said one second side wall slidably engaging said cutout edge also in the region of said cut-out, and said shorter extension of said other second side wall slidably engaging said cutout edge only outside of said cut-out, said other second side walls being longer than the transverse distance between said free edges of said channel-shaped end portions, and the length of said other second side wall from the inner end of its longer extension to the outer free end of said shorter extension being shorter than the distance between the deepest point of said cut-out in said one corner and the diagonally opposite corner of said rectangular opening so that said shorter extension passes through said cut-out only when the respective other second side wall is placed in contracted position of said link strap in the diagonal of said rectangular opening whereby said second links can be threaded through said cut-outs for removal, said one second side wall of each second link being located opposite said one of said first side walls of the associated first link; and a set of curved leaf springs, each leaf spring being located between a first side wall and a second side wall to urge said link chain into a contracted position, each leaf spring having end portions projecting into said channel-shaped end portions, each end portion of said leaf springs having a recess matching the respective free edge of said channel-shaped portion and being spaced from the same to permit moving apart of said end portions when said curved leaf spring is compressed.
